A. H. WEHMILLER,
METHOD OF PASTEURIZING LIQUIDS,
APPLICATION FILED FEB. 7, 1916.

Patented May 22, 1917.
2 SHEETS—SHEET 2.

ATTYS.

UNITED STATES PATENT OFFICE.

ALFRED H. WEHMILLER, OF ST. LOUIS, MISSOURI, ASSIGNOR TO BARRY-WEHMILLER MACHINERY COMPANY, A CORPORATION OF MISSOURI.

METHOD OF PASTEURIZING LIQUIDS.

Specification of Letters Patent.

Patented May 22, 1917.

1,227,101.

Application filed February 7, 1916. Serial No. 78,616.

To all whom it may concern:

Be it known that I, ALFRED H. WEHMILLER, a citizen of the United States of America, a resident of the city of St. Louis, State of Missouri, have invented certain new and useful Improvements in Methods of Pasteurizing Liquids, of which the following is a full, clear, and exact description, reference being had to the accompanying drawings, forming a part of this specification.

My invention relates to improvements in the art of pasteurizing liquids contained in bottles or other receptacles, one of the objects being to provide an economical method of pasteurizing bottled liquids. More specifically stated, my object is to cause a thermic circulation of the bottled liquid by shifting the bottles while they are subjected to the action of the pasteurizing fluid, thereby insuring a more rapid pasteurizing action and at the same time economizing in the use of the heating medium.

Prior to this invention bottled liquids have been conducted through pasteurizing fluid in such a manner that the bottles are held in upright positions, the necks of the bottles being usually uppermost throughout the pasteurizing operation. In some of the prior pasteurizers the bottles are tilted slightly while entering or passing out of the pasteurizing fluid, but this movement of the bottles does not result in the accomplishment of the results to be hereinafter described.

The ordinary method of pasteurizing bottled liquids consists in placing the bottles in an endless carrier which travels slowly through the pasteurizing fluid without inverting or otherwise turning the bottles. The liquid in the upright bottles does not completely fill the bottle necks and since these necks contain only a small percentage of the contents of the bottles the following action takes place:

When the upright bottles enter the hot pasteurizing fluid, heat is transmitted to all parts of the bottles, but the temperature of the bottle necks soon becomes higher than the temperature of the bodies. This is due to the fact that the comparatively small necks contain a very small percentage of the liquid and the heat of the pasteurizing fluid is quickly transmitted from the necks to all of the liquid contained therein. Since the body of each bottle contains a very large

percentage of the liquid, the temperature of the body does not rise as rapidly as the temperature of the neck, it being necessary to transmit the heat from the body to all points throughout the comparatively large volume of liquid contained therein. It is important to note that in carrying out this old method the liquid at the partially filled upper end of each bottle is heated throughout at the beginning of the pasteurizing operation, while the liquid in the body of the bottle is heated very slowly. Since the comparatively hot liquid is always at the top of the bottle the liquid will not circulate from the hottest part of the bottle to the large volume of liquid in the body of the bottle. Therefore, considerable time is required to obtain a uniform sterilizing temperature at all points throughout the bottled liquid.

In carrying out my method, each bottle is turned while in the pasteurizing fluid, thus placing the hottest liquid at a point from which it will circulate through the cooler liquid, also placing the hottest portion of each bottle in a position where it will transmit heat to the comparatively cool liquid. This causes a thermic circulation of the liquid in the bottles and the bottled liquid is soon raised to the desired uniform temperature throughout by the rapid transmission of heat to all points throughout the liquid.

Figure I is a vertical section, partly broken away, illustrating a pasteurizer adapted for use in carrying out my method.

Fig. II is a diagrammatical view showing how the bottles are turned from one position to another as they travel through the pasteurizer.

Fig. III is a fragmentary view illustrating another apparatus adapted for use in carrying out my method.

Fig. IV is an enlarged detail view of one of the rotatable bottle carriers shown in Fig. III.

The pasteurizer shown in Figs. I and II comprises a tank having end walls 1 and 2, a bottom 3 and a cover 4. Partitions 5 and 6 extend downwardly from the cover 4 to points near the bottom of the tank. 7 and 7' designate partitions extending upwardly from the bottom of the tank. Heat is transmitted from steam pipes 8 to the pasteurizing fluid between the partitions 7 and 7'. 9

designates a steam pipe for heating the at-
temperating fluid between the partitions 5
and 7'.

- The bottle carrier comprises an endless
chain 10 fitted to suitable sprocket wheels as
shown in Fig. I and adapted to travel
through the pasteurizer. 12 designates bot-
tle holders secured to the sprocket chain 10.
The bottle carrier travels in the direction in-
dicated by arrows in Figs. I and II, the bot-
tles containing the liquid to be pasteurized
being placed in the bottle holders before the
latter reach the attemperating fluid between
the partition 5 and the end wall 1. The bot-
tled liquid is conducted downwardly through
the attemperating fluid between the parti-
tion 5 and end wall 1, then under the parti-
tion 5 and upwardly through the attemper-
ating fluid between the partitions 5 and 7'.
After passing from the attemperating fluid
the bottled liquid is conducted downwardly
and then upwardly in the hot pasteurizing
fluid between the partitions 7 and 7'. There-
after, it is carried through the cooling fluid
on opposite sides of the partition 6. The
bottle holders may be opened and closed
in any suitable manner, and the bottle car-
rier may be driven by any suitable power
mechanism.
- Figs. I and II clearly show that the bottles
are turned from one position to another while
they are submerged in the attemperating,
pasteurizing and cooling fluids, and as a con-
sequence a thermic circulation of the bottled
liquid is created during the different stages
of the heating and cooling operations. For
example, when a bottle is passing down-
wardly in the pasteurizing fluid, as indicated
at A in Fig. II, the comparatively small
volume of liquid in the bottle neck is heated
very rapidly, this being due partly to the
fact that the heat will be quickly transmitted
through the small volume of liquid and
partly to the fact that the level of the liquid
is at a point below the upper end of the
bottle. Hence the temperature of the upper
portion of the bottle soon becomes higher
than the temperature of the lower portion of
the bottle. After the bottle has been placed
in this condition it is inverted to the position
indicated at A' in Fig. II, and conducted
upwardly in the pasteurizing fluid. By
turning, or inverting, the bottle in this man-
ner the hottest portion of the bottle is placed
below the liquid contained therein, thereby
causing a thermic circulation of the liquid

in the bottle with the result of transmitting
heat very rapidly to all points throughout
said liquid. In traveling downwardly as in-
dicated at A in Fig. II, the glass bottle it-
self, and more particularly its neck and
stopper, becomes very hot, and when the bot-
tle is inverted to the position shown at A'
the circulating liquid contacts directly with
the hot bottle neck and stopper, thus facili-
tating the thorough pasteurization of all of
the liquid in the bottle. It will, therefore,
be understood that my method possesses
three advantages, namely, economy in the
use of the heating medium, rapid pasteuri-
zation, and a thorough pasteurization of all
of the liquid in the bottles.

The apparatus shown in Figs. III and IV
comprises sprocket chains 10' and bottle
holders 12' rotatably fitted to said chains. 75
Each bottle holder 12' is provided with a pinion 15 adapted to mesh with a long rack
bar 16. When the sprocket chains 10' are in
motion the pinions 15 travel along the rack
bar 16, thus turning the bottle holders con- 80
stantly during the different stages of the
pasteurizing operation. Each bottle holder
12' is preferably provided with a series of
radial bottle receiving pockets as shown in
Fig. IV. A constant thermic circulation of 85
the bottled liquid is insured by turning the
bottle holders constantly while they travel
through the pasteurizing tank.

I claim:—

1. The improvement in the art of pasteur- 90
izing liquids in containers which comprises
conducting the containers through an at-
temperating fluid, then through a pasteurizing
fluid, thereafter through a cooling fluid,
and causing a thermic circulation of the 95
liquid in the containers by turning said con-
tainers while they are submerged in the at-
temperating, pasteurizing and cooling fluids.

2. The improvement in the art of pasteur- 100
izing bottled liquids which comprises con-
ducting the bottles containing the liquid
through a pasteurizing fluid so as to raise
the temperature of the upper portions of the
bottles to a higher degree than the tempera-
ture of the lower portions of the bottles, and 105
then causing a thermic circulation of the
bottled liquid by turning each bottle suffi-
ciently to place its hottest portion in a lower
plane than the comparatively cooler liquid
in the bottle.

ALFRED H. WEHMILLER.
